UNITED STATES PATENT OFFICE.

LEWIS P. HALLADAY, OF STREATOR, ILLINOIS.

AUTOMOBILE-BUFFER.

1,121,828.

Specification of Letters Patent. Patented Dec. 22, 1914.

Application filed September 19, 1913. Serial No. 790,608.

To all whom it may concern:

Be it known that I, LEWIS P. HALLADAY, a citizen of the United States, residing at Streator, in the county of La Salle and 5 State of Illinois, have invented a certain new and useful Improvement in Automobile-Buffers, of which the following is a specification.

My invention relates to buffers for automobiles and has for its object to provide a new and improved device of this description.

The invention is illustrated in the accompanying drawings, wherein—

15 Figure 1 is a side elevation of one buffer support; Fig. 2 is a plan view; Fig. 3 is a cross section along line 3—3 of Fig. 1; Fig. 4 is a cross section along line 4—4 of Fig. 1; and Fig. 5 is a side elevation of the 20 end of the frame, with a section of a part of the buffer arm.

Like parts are indicated by like letters throughout the several figures.

A is a spring secured to the part B from 25 which projects the extension C within the frame, which at this point consists of the side piece D, the upper piece D¹ and the lower piece D². These parts are held together by the rivet D³, having the project- 30 ing heads D⁴, D⁵.

The buffer support consists of the tubular part E with the enlarged extension E¹, having the perforated wings E², E³ formed on the downwardly projecting flanges E³, E². 35 On the forward end of the extension E¹ and at one side is a downwardly and inwardly projecting reinforced portion E⁴, provided with a set screw E⁵, adapted to bear against the under side of the frame portion D¹.

40 F is a yoke preferably shaped so as to go around the rivet head D³ and secured by means of the bolts F¹ to the wings E², E³.

The extension E¹ is provided with two bearing surfaces G, G¹ which rest upon the 45 frame part D¹. The bearing surface D¹ terminates in an end or stop G, which is adapted to bear against the rivet head D³.

J is the transverse channel-shaped buffer bar secured at each end by means of a bolt 50 J¹, which passes through the adjustment slot J², at the bottom of the channel. There is an extension J³ on the end of the socket J⁴ into which the end E of the buffer support is inserted in the usual manner. The buffer 55 support E should be slidable in the part J⁴

and backed up against a spring or spring buffer.

I do not wish to be limited to the precise form, arrangement and proportion of the several parts, as they may be modified without departing from the spirit of my invention.

The use and operation of my invention are as follows: I have shown my device as applied to the ordinary form of automobile 65 frame end. If the curvature of the frame differs very radically from a given standard type, it may be necessary to have one or more varying forms of the device, but assuming that it is to be used on a frame of 70 substantially the curvature shown, then the buffer support will be shaped as indicated. To insert or place the support in position, it is inclined to one side until the part E⁴ is inserted between the upper and lower parts 75 D¹ and D² of the frame, whereupon if the buffer support be righted, its two depending side parts, E³, E² will inclose the frame, as indicated in the Figs. 3 and 4, and the stop G¹ will rest against the rivet heads D⁴, as 80 indicated in Fig. 5. The set screw E⁵ is now forced firmly into position to hold the parts together. The yoke F is then placed in position and the parts securely drawn together by means of the bolts F¹, F². Thus 85 the buffer support incloses the upper portion of the frame, is rigidly clamped thereto and has a firm bearing against the rivet head thereof. At the same time the parts are all held in proper relation by means of 90 the yoke and bolts. Since the support has but two bearings on the upper surface of the upper part of the frame, it will accommodate itself to a wide variety of frame forms. It lies wholly above the end of the 95 frame and can be used when, as is frequently the case, the lower part of the frame has an extended apron projecting inwardly to protect the radiator above.

I claim:

1. A support for an auto buffer comprising a body resting upon the upper part of the frame near the spring end provided with means to engage the lower surface of such upper part of the frame at a distance from the spring end to hold the body to the frame, additional means to secure the body to the frame near the spring end and downwardly depending sides to clasp the edges of the upper part of the frame. 105 110

2. A support for an auto buffer comprising a body shaped to conform to the curvature of and resting upon the upper part of the frame near the spring end and provided with downwardly depending sides which clasp the edges of the upper part of the frame, a rivet head on the frame, a stop which engages the rivet head above the frame, a clamp and set screw hung below the upper part of the frame at a distance from the spring end to clamp the frame in combination with a clip underlying the

lower part of the frame near the spring end and shaped to avoid engagement with the rivet head and bolts whereby such clip and 15 the body are drawn together to hold the parts in position on the frame.

In testimony whereof I affix my signature in the presence of two witnesses this 16th day of September, 1913.

LEWIS P. HALLADAY.
